Inventor

GEORGE SHARP, OF PHILADELPHIA, PENNSYLVANIA.

Design No. 3,425, dated March 23, 1869.

DESIGN FOR A SPOON OR FORK-HANDLE.

The Schedule referred to in these Letters Patent and making part of the same.

To all whom it may concern:

Be it known that I, GEORGE SHARP, of the city of Philadelphia, in the State of Pennsylvania, have invented or produced a new and original Design for the Handles of Spoons, Forks, and other articles of table-use requiring shank-handles, of which the following is a full, clear, and exact description, reference being had to the accompanying drawings, making a part of this specification.

Referring to the said drawings—

Figure 1 is a plan view, and

Figure 2, a side view of a teaspoon, having my said design for handles applied thereto.

Like letters of reference indicate the same parts when in both figures.

My design consists of the configurations and ornaments shown on that part of the handle which extends from A to B in the said figs. 1 and 2.

What I claim as my invention, and desire to secure by Letters Patent, is—

The design for the handles of spoons, forks, and other articles of table-use requiring shank-handles, herein set forth and shown.
